UNITED STATES PATENT OFFICE.

JAMES F. HAFFEY, OF TIFFIN, OHIO, ASSIGNOR TO CHARLES S. BARON,
OF TIFFIN, OHIO.

JUG-TOP.

No. 838,586.

Specification of Letters Patent.

Patented Dec. 18, 1906.

Application filed March 24, 1905. Serial No. 251,871.

To all whom it may concern:

Be it known that I, JAMES F. HAFFEY, of Tiffin, county of Seneca, State of Ohio, have invented certain new and useful Improvements in Jug-Tops, of which the following is a specification.

The object of my invention is to produce improvements in metallic tops for fragile vessels, and particularly in molasses-jug tops, in which all the metallic parts are assembled and combined without the use of solder and in which improved means are provided for attaching the metallic and the fragile members together.

In the accompanying drawings, which form a part of this specification, Figure I is a central vertical section of one of my tops in one of its forms of embodiment and of the neck of a molasses-jug to which it is attached, the lid 5 of the top being shown in a closed position. Fig. II is a top plan view of the subject-matter of Fig. I with the lid open. Fig. III is a perspective view of an assembling-cylinder detached, showing the upper part thereof ready for the reception of the collar and rim and before it is crimped. Fig. IV is a view similar to Fig. III, showing a modified form 15 of the assembling member in which said member is incorporated with the lip of the jug-top. Fig. V is a view similar to Fig. I, showing that modified form of embodiment of my invention in which the assembling member shown in Fig. IV is assembled, with rim and collar, and crimped to hold the several parts united. Fig. VI is a sectional view 20 illustrating of a modified means of uniting the collar or top to the jug-neck.

Referring to the numerals on the drawings, 1 indicates, by way of example, the neck of a fragile vessel or receptacle, such as a molasses-jug, to which is attached a metallic top. The top consists of a collar 2, a rim 3, and a lid 4, hinged to the rim, as indicated at 5, the lid being preferably provided 25 with a spring-actuating hinge 6. (Shown clearly in Fig. II.) The lid and its hinge connection are well understood in the art. It is to the collar and rim and means of assembling the same that my invention directly 30 appertains.

The collar is provided with an inturned annular flange 8, and the rim with a coextensive inturned annular flange 9, which flanges when laid face to face, as illustrated in Fig. I, con-

stitute, in effect, a single annulus of double thickness. For permanently uniting the annuli 8 and 9 in their assembled relations I provide a special assembling member, which preferably consists of a cylinder, as shown in Fig. III and in a modified form in Fig. IV. The assembling member is preferably drawn in one piece of metal in the shape of a cylindrical skirt 10, a crimping-cylinder 11 of somewhat contracted diameter as compared with the cylinder 10, and an intermediate annular shoulder 12, formed by the contraction of the cylinder 11.

In practice the flange 8 of the collar, which fits snugly around the cylinder 11, is set against the shoulder 12. The flange 9 of the rim is then slipped into place upon the cylinder 11 in close juxtaposition to the flange 8. Then by the aid of a suitable machine well known in the art of sheet-metal working the cylinder 11 is crimped—that is, lapped or bent over against the outer face of the annulus 9, as shown in Fig. I—the permanent flexion of the metal of the cylinder 11 serving without the use of solder to hold the several members in their assembled relations, as described.

15 indicates the jug-lip, which, being made of plate metal suitably shaped, is also secured to and made a part of the jug-top without the use of solder. It may, for example, be provided with a crimped bend 16, which, as shown in Figs. I and II, infolds and so by permanent flexion of the metal of which it is composed fastens upon the previously shaped and crimped cylinder 11. 90

While it is practicable to form the lip 15, as above described, of a separate sheet of metal from the assembling member, I prefer to form it integral therewith, as illustrated in Figs. IV and V. In those figures, 16 indicates the skirt of the assembling member, 17 the shoulder, and 18 the contracted crimping-cylinder, all substantially identical with the assembling member shown in Fig. III, save and except that the cylinder 18 is provided upon one side with an extended portion 19, shaped to constitute the jug-lip. The manner of uniting the assembling member shown in Fig. IV to the collar and rim is substantially identical with that previously 105 described, except that the crimping flexion 20 of the assembling member, which is formed in the upper part of the cylinder 18,

in so far as it resembles the cylinder 11, includes and extends across the body part or metal portion of the lip extension 19 of the cylinder 18, as clearly shown in Fig. V.

5 One of the advantages derivable from my invention in addition to the economic and sanitary method employed in assembling parts without the use of solder is in the greater security afforded in the presence of 55
 10 the depending skirt of the assembling member for uniting the jug-top to the jug. The skirt of the assembling member is preferably cylindrical, like the collar 2, and coaxial therewith, the space between them being prefer-
 15 ably sufficient to snugly accommodate the neck of the jug. For uniting the jug-top to its neck a suitable engagement between the parts may be derived by a bend or groove formed in one of the metallic members of the
 20 top which go around the neck. The collar 2 may, for example, be provided, as by the use of a suitable machine, with a bead 22, engaging and fitting over a bead 23, provided for it on the outside of the neck. On the other
 25 hand, the skirt 10 (see Fig. 1) may be grooved, as indicated at 24, into an annular depression 25, provided for it in the inner wall of the neck. If the beads 22 and 23 be preferred as the means for securing the parts together,
 30 the skirt 16, which corresponds to the skirt 10 of the assembling member, may be made of true cylindrical shape to conform with that of the usual shape of a jug-neck, and the lower edge of the skirt is then preferably in-
 35 serted behind the annular lip 26, formed in the inner wall of the neck of the jug to receive it.

In Fig. VI, I show a slotted and resilient skirt 10 upon everted edge 28, may be, by 40 the resilient force of the skirt, urged and held in engagement with a groove 25, above referred to, in the inner wall of the neck 1. Such engagement is sufficient to unite the parts in ordinary use, but may yield to the 45 application of a gentle force directed to the purpose of separating them—as, for instance, in the event of breakage of the jug proper. In such case if the top were of value it might be applied to a succession of fragile vessels 50 of indefinite number.

What I claim is—

1. In a jug-top, the combination with its collar and rim provided respectively with corresponding annular flanges, of an annular assembling member, crimped about the edges 55 of said flanges and thereby securely uniting the collar and the rim, said assembling member being provided with a depending skirt.

2. In a jug-top, the combination with its collar and rim provided respectively with 60 corresponding annular flanges, of an annular assembling member crimped about the edges of said flanges and thereby securely uniting the collar and the rim, said assembling member being provided at one end with a depend- 65 ing skirt and at the other with a lip formed integrally therewith.

3. The combination with the flanged collar and rim of a jug-top, of an assembling member consisting of two cylinders of different diameters and an intermediate shoulder, the smaller cylinder being crimped to unite the collar and rim together, and the larger cylinder extending coaxially with the collar. 70

4. The combination with a jug provided 75 within its neck with an internal annular lip, of a jug-top provided with internal and external coaxial cylinders, the inner cylinder being confined between said lip and the jug-neck, and means for securing the jug-top to 80 the neck.

5. The combination with a jug provided within its neck with an internal annular lip, of a jug-top provided with internal and external coaxial cylinders, the inner cylinder 85 being confined between said lip and the jug-neck, and means for securing the outer cylinder to the jug-neck.

6. The combination with a jug, of a top provided with a collar, a rim, and a member 90 fitting the interior of the jug-neck and uniting said collar and said rim.

In testimony whereof I have hereunto signed my name in the presence of two subscribing witnesses.

JAMES F. HAFFEY.
